DESIGN FOR A CHILD'S CAPE

Jerome M. Schwartz, New York, N. Y.

Application February 6, 1942, Serial No. 105,669

Term of patent 3½ years

To all whom it may concern:

Be it known that I, Jerome M. Schwartz, a citizen of the United States of America, residing in New York city, county of New York, and State of New York, have invented a new, original, and ornamental Design for a Child's Cape, of which the following is a specification, reference being had to the accompanying drawing, forming part thereof, wherein,

I claim:

The ornamental design for a child's cape, substantially as shown.

JEROME M. SCHWARTZ.
